UNITED STATES PATENT OFFICE.

JOHN F. NICHOLS, OF FALL RIVER, MASSACHUSETTS.

TOP-ROLL-GRINDING MACHINE.

SPECIFICATION forming part of Letters Patent No. 448,300, dated March 17, 1891.

Application filed November 28, 1890. Serial No. 372,819. (No model.)

To all whom it may concern:

Be it known that I, JOHN F. NICHOLS, of the city of Fall River, in the county of Bristol and State of Massachusetts, have invented 5 certain new and useful Improvements in Top-Roll-Grinding Machines, of which the following is a full, clear, and exact description, reference being had to the accompanying drawings, forming part of this specification.

10 This invention has reference to improvements in mechanism for grinding the drawing-surfaces of top rolls, which are formed of metal rolls covered with leather or similar material, the object being to produce a mechanism which will grind the surface of the rolls 15 in such a manner as will insure a perfect cylindrical surface parallel with the line of the axis of the rolls.

The invention consists in the novel features 20 of construction of the grinding-machine and their combination with any ordinary form of a back-geared lathe, as will be more fully set forth hereinafter, and pointed out in the claims.

25 Figure 1 is a view of an ordinary back-geared lathe with the grinding mechanism attached thereto. Fig. 2 is an enlarged side view of the grinding device, showing the grinding-wheel in contact with the top roll.

30 Similar numbers of reference designate corresponding parts throughout.

In the drawings, 3 designates the lower part of a case provided with the chute 4 and cup 5 and supported by the brackets 6, 35 which are secured to a plate adjustably fitted to the slide-rest 7. In the upper ends of the brackets 6 is journaled the shaft 8, which carries the grinding-wheel 9 and is supplied with the small pulley 8'. The wheel 9 is provided

40 with a removable section 10, which is secured to the main portion of the wheel by the screw 11 and thumb-nut 12. The case 3 is provided with a hinged cover 13, which has a projecting lip to extend over the top roll 14

45 when the cover is closed. Motion is imparted to the grinding-wheel 9 by means of a belt 15, working on the pulley 8' and driven from a drum 16, which is of a length equal to the length of the top rolls and has a diameter considerably greater than the diameter of the pulley 8'. The grinding-surface of the wheel

9 is formed of a strip of sand-paper or other suitable material. In securing the grinding-surface to the wheel the section 10 is first removed. The strip of sand-paper is then placed 55 around the wheel and the ends turned into the opening formed by the removal of the section 10. A shorter strip of sand-paper is then placed over the face of the section 10 and the ends bent over the ends of the section. The section 10 is now replaced in the wheel 9 and screwed in place by means of the screw 11 and nut 12, stretching the strips of sand-paper tightly over the face of the wheel 60 and section 10. 65

The operation of the improved grinding device is as follows: The top rolls 14 are first centered and secured in the lathe. The plate forming the base for the brackets 6 is then fastened to the slide-rest 7 in a position to 70 bring the grinding-wheel against the surface of the top roll, as shown in Fig. 2. The slide-rest 7 is now thrown into gear with the worm-gear of the lathe and motion is imparted to the shaft carrying the lathe-driving pulley 75 and the drum 16, from which the motion is conveyed by belts to the lathe-pulley and to the grinding-wheel, thus turning the top rolls 14 and grinding-wheel 9 in the same direction, but at different speeds, while the grinding device is carried by the slide-rest along the entire length of the top rolls in a line directly 80 parallel with the line of their axes, the belt 15 being moved along over the drum 16 at the same time. During the grinding operation 85 the dust and particles of leather are caught in the cup 5 and are carried by the current of air created by the grinding-wheel to the chute 4, being thus conveyed away from the top roll. 90

I have found in practice that the above mechanism for grinding top rolls will produce a more perfect drawing-surface, which will necessarily be parallel with the axis-line of the rolls. 95

Having thus described my invention, I claim as new and desire to secure by Letters Patent—

1. In a grinding-machine for top rolls, the combination, with a lathe in which the top rolls are centered and secured, of a grinding mechanism contained in the case 3, having 100

the cover 13 and provided with the cup 5, chute 4, and brackets 6 6, by which it is supported on a plate secured to the slide-rest of the lathe, as and for the purpose described.

5 2. In a grinding-machine for top rolls, a case formed in two parts to contain a grinding-wheel and furnished with a cup projecting under the top roll during grinding to col-

lect the particles ground therefrom and a chute through which the particles are conveyed, as described.

JOHN F. NICHOLS.
